PLAYHOUSE

Donald M. Warren, West La Fayette, Ind.

Application August 11, 1933, Serial No. 684,686

7 Claims. (Cl. 46—37)

The objects of the invention are to provide an improved play-house of the class described which may be made of substantially flat sheet units which may be readily assembled and disassembled at will; to provide a house of the class described which may conveniently be packaged for transportation and storage purposes; to provide a house of the class described which will be strong and rigid when set up and which will be effectively held in set-up position; to provide a play-house structure in which a portion of a box, used for packaging the play-house when knocked down, is adapted to constitute a part of the set-up house; and in general, it is the object of this invention to provide an improved play-house of the class described.

Other objects and advantages of the invention will be understood by reference to the following specifications, and accompanying drawings (two sheets) in which a play-house embodying a selected form of the invention is illustrated.

In the drawings:

Fig. 1 is a front elevation, certain portions being broken away and shown in section to more clearly illustrate the construction.

Fig. 2 is an end elevation of the right hand end of Fig. 1.

Fig. 3 is a rear elevation.

Fig. 4 is a section on the line 4—4 of Fig. 3, and Figs. 5, 6, and 7 are detail elevations illustrating the means for connecting the various parts of the structure.

Referring now to the drawings, the play-house or doll-house illustrated in the drawings includes a main house, portion 10, and a sun-porch portion 11, which is secured to one end of the main portion 10.

The main house section 10 is set up on a base element 12, which may conveniently consist of a box section, either the top or bottom part of a relatively shallow box in which the other portions of the play-house are packaged for distribution or storage. As indicated the base member 12 includes a main wall portion 13, which constitutes the floor of the house, and depending side flanges 14 which rest on whatever surface the house is placed upon.

The front wall 15, generally rectangular in shape and of suitable card-board or other sheet material, is provided at its bottom edge with a plurality, in this instance four tongues, or ears designated 15a, which project through suitable openings 13b provided in the floor 13.

The ears and the openings just referred to and those hereinafter mentioned are preferably of a

shape which results in an especially rigid yet separable connection of the parts and which shape will presently be described.

In the following description ears formed integral with a part will be designated by the reference numeral for the part with the exponent *a*, and openings in a part will be designated by the reference numeral for the part with the exponent *b*.

End walls 16 and 17 are provided, and these end walls are each provided with ears designated 16a and 17a respectively, such ears being adapted to project through openings 15b adjacent the respective ends of the front wall 15. The end walls 16 and 17 are also provided with ears 16a and 17a on their bottom ends, such ears being adapted to project through openings in the floor member 13. It will be seen that the end members 16 and 17 are attached by means of their ears to both the floor member 13 and the front wall 15. In as much as the connecting ears and openings are such as to firmly hold the parts together, it will be apparent that the front wall serves to space the end walls apart, and to maintain them in substantially parallel up-right relation. Also that the end walls effectively maintain the front wall in substantially vertical position, i. e., perpendicular to the floor part 13, it being understood of course that the front and rear edges of the end members are disposed at substantially right angles to the bottom edges thereof, as shown in the drawings.

The roof member 18 which may conveniently be in the form of one piece, has a score line intermediate its width to facilitate its bending as at 19, to permit the roof member to assume a peaked shape to fit the angularly disposed top edges 16c and 17c on the respective end members. To lock the roof member in place, it is provided with openings such as 18b for receiving ears 16a and 17a, extending from the upper edges of the respective end members.

The chimney 20 preferably made of four pieces of sheet material is mounted on the roof in any desired location. The chimney consists of end pieces 21 and 22 respectively and front and rear side pieces 23 and 24 respectively. These pieces are connected in rectangular formation by means of ears 23a and 24a extending from the opposite edges of the pieces 23 and 24 and projecting through openings 21b and 22b in the respective end members 21 and 22. For mounting the chimney on the roof, the roof is provided at any desired location with additional openings 18b adapted to receive ears 23a and 24a, which

depend from the side members 23 and 24 respectively.

The structure thus far described constitutes what may be termed a shell in that it consists of merely the floor, front, ends, and roof, which parts are sufficient to present the outward appearance of a toy house. As indicated in Figs. 1 and 2 of the drawings, the front and end walls of the structure are embossed, printed, or otherwise provided with representations of doors, windows, etc. In this instance it is preferred to punch openings in the front wall 15 to represent windows, such openings being surrounded with suitable embossed representations of window frames. Also the door illustrated in Fig. 1 of the drawings is preferably formed so that it may be opened or closed, this being accomplished by slitting the wall as indicated at 25 and 26, and by scoring the wall as indicated at 27 to permit the door portion to be bent inwardly or outwardly from the normal plane of the front wall.

To more or less simulate the interior division of a house into rooms the play-house is provided with a second-floor partition 28 intermediate the floor part 13, and the roof part 18. The partition 28 is provided with ears 28a extending from its opposite ends and its front edge and adapted to project through additional openings 15b, 16b, and 17b in the front and end walls respectively.

To support the second-floor partition 28 intermediate its length, there is provided a vertical partition 29, this partition being provided with tongues or ears 29a extending from its top and bottom edges respectively and projecting through openings 28b and 13b in the partition 28 and floor 13 respectively. The vertical partition 29 is preferably of less width than the full width 40 of the house so that a space is left between the front edge of the partition and the front wall, as clearly shown in Fig. 4. Another partition or stay member 30 is disposed adjacent the front edge of partition 29 and in transverse relation thereto, as clearly illustrated in Figs. 3 and 4. The member 30 is rigidly secured in place by means of tongues 29a extending from the front edge of the member 29, and projecting through openings 30b in the member 30 and by means of a tongue 30a extending from the lower edge of the member and projecting through an opening in the floor member 13. It will be seen that the arrangement of the partition member 30 serves to form a wall spaced inwardly from the door in the front wall of the house. In other words it serves to provide a space in the nature of a vestibule in the house. Also the partition element 30 serves to prevent swaying of the house in a lengthwise direction by reason of its top and bottom edge engagement with the upper and lower floor members. Because of the connection of the member 30 to the partition 29 it will be seen that if the member 29 is caused to swing about either its upper or lower edge as a pivot the member 30 would be required to move with the member 29 as a rigid unit. Such movement however is effectively resisted by the said engagement of the upper and lower ends of the member 30 with the upper and lower floor elements.

Another vertical partition 31 is provided substantially in continuation of the lower partition 29, the member 31 being provided with ears 31a depending from its lower edge and projecting through openings provided in the floor partition

28. It will be observed that two of the ears 31a extend downwardly through the same openings in the floor partition 28 that receive the upwardly projecting ears 29a of the lower vertical partition 29. This is readily permitted by reason of the inherent give and resiliency of material such as card-board. The upper end of the partition 31 is preferably shaped to fit the roof, as clearly shown in Fig. 4 and ears 31a project upwardly through the openings 18b of the roof.

The structure thus far described consists in itself a complete play-house. However, to render the structure more attractive, it may be provided with the sun porch 11, previously referred to. In this instance, the sun porch is formed of front and rear members 32 and 33 respectively, and an end member 34. The members 32 and 33 are provided with ears 32a and 33a respectively, which project through openings in the end wall 17 for connecting the said front and rear members to said end wall. The sun porch end wall is similarly connected to front and rear walls 32 and 33 by means of tongue and opening connections as clearly indicated. The floor member 35 is provided at its front, rear, and outer end edges with ears designed to project through openings in the respectively adjacent sun porch wall members and the inner end edge of the floor member 35 is adapted to be positioned as indicated at 35c on the marginal portion of the base member 12 outwardly of the end wall 17. The roof member 36 is mounted on the top edges of the sun porch walls by means of ears projecting upwardly from the respective walls, and extending through openings in the roof member 35 and by means of ears extending from the inner edge of the roof member through openings in the adjacent wall member 17. A sort of decorative railing may conveniently be mounted on the roof member and formed of front and rear members 38 and 39 respectively and an end member 40. The members 38 and 39 are provided with tongues 38a and 39a, which project through suitable openings in the end member 17, and the end rail element 40 is provided with tongues on each of its ends, which tongues are adapted to project through opening in the adjacent ends of the members 38 and 39. The rail members 38, 39, and 40 are also provided with depending ears which project through suitably located openings in the roof member 36.

The tongue or ear, and opening connections above referred to may be in the form of plain ears and slots made so that the tongues or ears will snugly fit in the slots. However such an arrangement does not long retain any degree of rigidity since the fit of the tongues in the slots soon becomes loose, with consequent loosening of connections at all points, with the result that rigidity of the structure is lost. In this instance it is preferred to make the ears and openings substantially as illustrated in Figs. 5, 6, and 7.

As shown in Fig. 5 the ear designated "a" is provided with an intermediate enlarged portion having a width designated W, which is somewhat greater than the inner end width I. The outer end width O of the ear is preferably considerably smaller than both the intermediate and inner end widths, as clearly shown.

The openings are preferably of a form which provides a sort of clamping or wedging effect on the side edges of the ears, which are projected through the openings. In this instance the openings are in the form of square or triangular openings, as shown in Figs. 6 and 7, the square

openings being arranged with their diagonals disposed in the direction of the ears which they are to receive. The diagonal dimension of the square openings as shown in Fig. 6 is preferably such that when first cut it is a very snug fit, or possibly slightly smaller than the inner width of the ear "a". It will be understood that in connecting a member having an ear "a" to a member having a square opening, the intermediate width W of the ear must be forced through the opening. In doing this the oppositely disposed corners of the opening are subjected to considerable force by the enlarged width W of the ear, and the opening is perhaps enlarged by the passage of the width W of the ear therethrough. Also the width W of the ear is probably reduced slightly under the constraining effect of the member having the square opening. When the inner width I of the ear is positioned in the opening, the angularly disposed sides of the opening which engage the opposite side edges of the ear appear to have a sort of wedging action on the ear to effectively and rigidly connect the parts. The enlarged intermediate width W of the ear obviously serves to resist withdrawal of the ear from the opening. It will of course be manifest that card-board or similar sheet material has an inherent degree of resiliency, which facilitates the connecting of the parts by the above described means.

In some instances, for example when the openings are disposed adjacent the edges of a member, it is preferable and convenient to provide triangular openings as illustrated in Fig. 7. It will be readily seen that by comparison of Figs. 5, 6, and 7 that a tongue may be projected through the triangular opening with substantially the same effect as obtained when the tongue is projected through the square opening shown in Fig. 6. In Figs. 5, 6, and 7 the lines e and f serve to facilitate a comparison of the preferred proportions of the ear with respect to the openings through which it is to be projected. It will be evident that openings of other shapes may also be used to obtain the same effect as obtained by the openings described.

It is extremely difficult to determine what the exact action is when ears such as described are projected through openings such as described. However so far as can be determined the above described action appears to be correct. It is also possible that the ear itself is subjected to slight buckling action in view of the restricted diagonal width of the opening. Under such condition, the normal resiliency of the material tends to constrain the tongue, with resulting tight fit in the opening.

The design of house disclosed in this instance is merely selected arbitrarily and obviously may be varied. If desired, a garage or similar structure may be attached to the other end of the house in substantially the same way that the sun porch herein described is attached to one end. Preferably, where a sun porch is attached to one end and a garage or the like is attached to the other, they are so arranged as to be interchangeable whereby some variation in the structure is possible. In some cases, where only one auxiliary structure is furnished, both ends of the main structure are provided with openings to permit the auxiliary structure to be attached to either end of the main structure. Many other attractive designs either of complete house structures or partial structure representing, for example, a single room, may be made by con-

necting members in the above described manner and other changes may be made in the described structure without departing from the spirit of the invention, the scope of which should be determined by reference to the following claims, the same being construed as broadly as possible consistent with the state of the art.

I claim as my invention:

1. A play-house comprising a plurality of sheet material members having means for uniting the same in set-up relation, said means comprising ears integral with and projecting edgewise from some of the members and openings in some of the members having niches adapted to wedgingly engage the edges of said ears when the latter are projecting through the openings, the ears having inner end widths substantially fitting said openings, outer end widths less than the corresponding dimensions of said openings, and intermediate widths greater than said opening dimensions, said intermediate widths necessitating distortion of the ear or opening to permit passage of said intermediate width portion through the opening and serving to lock the members in set-up relation.

2. A house structure of the class described comprising a plurality of sheet material members adapted to be connected in set-up relation, and means for connecting the members comprising ears on some of said members and openings in others, the ears having inner end widths substantially fitting the corresponding dimensions of said openings, outer end widths less than the corresponding dimensions of said openings, and intermediate widths greater than said opening dimensions, said intermediate widths necessitating distortion of the ear or opening to permit passage of said intermediate width portion through the opening and serving to lock the members in set-up relation.

3. In a play-house of the class described, the combination of a base comprising an inverted box section including a bottom and side flanges, said bottom being provided with openings, front and end walls having ears depending from their lower edges and snugly fitting and projecting through said openings to thereby position the walls on the base, connection between said front and end walls whereby the latter cooperate with each other to maintain themselves in upright relation, said walls and base constituting a main house structure, a sun porch or similar auxiliary structure having ears projecting therefrom and said main structure having openings for receiving the ears of said auxiliary structure to thereby connect the main and auxiliary structures, and a floor member in said auxiliary structure having a marginal portion seated on a marginal portion of the base outwardly of the side wall to which the auxiliary structure is connected, and tongue and opening connections between the edges of said floor member and the respectively adjacent walls of said auxiliary structure.

4. A play-house structure comprising a floor member, front and end walls extending upwardly from said floor member, a roof supported on said walls, a partition extending substantially parallel with said end walls and terminating short of said front wall, a brace member secured to the front end of said partition and engaging said floor and serving to re-enforce the structure against endwise swaying movement.

5. In a play house of the class described, the combination of a base comprising an inverted

- paper board box section including integrally connected bottom wall and side flange portions, the latter serving to support the bottom at an elevation from a surface on which the play house 5 is set up, said bottom being provided with a plurality of relatively spaced openings extending therethrough, a pair of oppositely disposed paper board walls and another paper board wall extending between and connected with said pair of 10 walls adjacent corresponding edges thereof, said walls constituting outer walls of the play house and having ears depending from their lower edges and snugly fitting and projecting through said openings to thereby position said walls on 15 said base.
6. In a paper board structure comprising parts adapted to be connected together in relatively angularly disposed relationship, means for connecting the parts in such relationship comprising 20 an ear extending from one part and an opening in the other for receiving such ear, the ear having an inner end width approximately fitting the corresponding dimension of the opening, the outer end width of the ear being less than the 25 than the corresponding dimension of the opening, and the intermediate width of the ear being

greater than said opening dimension, said intermediate width necessitating distortion of the ear or opening to permit passage of said intermediate width portion through the opening and serving to lock the parts in their assembled relation.

7. In a paper board structure comprising parts adapted to be connected together in relatively angularly disposed relationship, means for connecting the parts in such relationship comprising an ear extending from one part and an opening in the other for receiving such ear, the ear having an inner end width approximately fitting the corresponding dimension of the opening, the outer end width of the ear being less than the corresponding dimension of the opening, and 15 both side edges of the ear being humped outwardly intermediate the inner and outer ends of the ear so as to provide an intermediate ear width greater than said opening dimension, said intermediate width necessitating distortion of 20 the ear or opening to permit passage of said intermediate width portion through the opening and serving to lock the parts in their assembled relation.

25

DONALD M. WARREN.
